SPRAY NOZZLE

Filed Sept. 2, 1930

INVENTOR:
INOJIRO KOBAYASHI.
BY ATTY:

UNITED STATES PATENT OFFICE

INOJIRO KOBAYASHI, OF HOLLYWOOD, CALIFORNIA

SPRAY NOZZLE

Application filed September 2, 1930. Serial No. 479,244.

This invention relates to improvements in nozzles, and its objects are to provide a nozzle with a plurality of spray orifices for covering greater area with a spray, to provide means for releasing pressure in the spray nozzle whereby it may be readily detached from a hose prior to shutting off the water supply, and to provide means for diminishing the area of the spray issuing from either orifice. The drawings illustrate a form of the invention which I have so far found to be the most practical in use, but I reserve the right to minor changes, alterations and modifications that may fall within the scope of the appended claims.

In the drawings: Figure 1 is a side elevation of a spray nozzle embodying the features of the present invention. Fig. 2 is a sectional elevation of the same. Fig. 3 is a front elevation of the spray nozzle. Fig. 4 is a sectional elevation of the nozzle with all movable parts removed. Fig. 5 is a top plan of the pressure release valve. Fig. 6 is a side elevation of the pressure release valve.

Referring to the drawings, the nozzle body 11, has a threaded part 12 adapted to engage with a hose (not shown), and has a hollow bore 13, and a standard 14 whereby it may be positioned and secured to the ground. Body 11 has an opening 15, normally covered by valve 16, which is retained in closed position by bail member 17, mounted on shaft 18, and engaging in groove 19, on valve 16. This allows the operator to release the water pressure in the hose, before going to the shut off valve therefor, and allows the operator to quickly remove the spraying nozzle. To release valve 16, the operator shifts bail member 17, rearwardly. The nozzle body 11 has an initial spray orifice 20 having suitable inclination for throwing the spray at the greatest distance. With orifice 20, no spray will be thrown close to the nozzle. A small opening 26 leads from the hollow bore 13 to an additional spray orifice 21, which is provided and is adapted for throwing the spray closer to the nozzle. For limiting the area of the spray, I provide side guards 22, each independently mounted on shaft 23, and provided with inner projections 24, adapted to en-

gage with corresponding sockets 25 in body 11. Either guide may be shifted and adjusted to shut off the spray on the corresponding side of the nozzle body, or both may be adjusted to throw spray in a narrow body 65 and direct line from the front face of the nozzle.

From the foregoing description and drawings, it may be seen that I have provided a spray nozzle, capable of delivering spray 60 over a large area, capable of spraying adjacent to the nozzle, and capable of throwing the spray to either side only relative to the position of nozzle and attached hose.

The guards which limit or shut off side dispersion of the spray, render the device especially advantageous in watering and irrigating gardens. The plurality of discharge orifices allow the spray to be dispersed over greater area, and adjacent to the spray nozzle. 70 When desired, the pressure release valve may be opened, thereby releasing pressure within the attached hose, and permitting the removal of the nozzle prior to shutting off the water pressure from the hose. 75

What is claimed is:

1. In a spray nozzle, a body member, having a plurality of spray orifices, said orifices extending on the top and either side of the body member, and means disposed on either 80 side of the body member for closing the spray orifices on the corresponding side.
2. In a spray nozzle, a body member having spray orifices disposed at different angles and extending on the top and either side 85 of the body member, and means for closing the orifices on either side of the body member.
3. In a spray nozzle, a body member having spray orifices across the top and on either 90 side thereof, and independently operable guards arranged to close the side portions of the spray orifices.
4. In a spray nozzle, a body member having a plurality of spray orifices, a pressure 95 release valve disposed at the rear of the orifices, and a bail member arranged to retain the release valve in closed position.
5. In a spray nozzle having a plurality of 100 spray orifices, and a pressure release open-

ing, a valve normally closing the pressure release opening, a bail member serving to retain said valve in closed position, and guard members arranged to close the side portions
5 of the spray orifices.

In testimony whereof, I hereunto affix my
signature.

INOJIRO KOBAYASHI.
